[57] CLAIM

The ornamental design for a speed control mechanism,
as shown and described.

DESCRIPTION

FIG. 1 is a side elevation view taken from the right of a
speed control mechanism embodying my new design;
FIG. 2 is a top plan view thereof;
FIG. 3 is a bottom plan view thereof;
FIG. 4 is a rear elevation view thereof;
FIG. 5 is a front elevation view thereof; and
FIG. 6 is a side elevation view thereof taken from the
left of FIG. 5.
